UNITED STATES PATENT OFFICE.

JAY HERBERT SMITH, OF NEW HOLLAND, GEORGIA.

LOOM ATTACHMENT.

Application filed May 6, 1922. Serial No. 558,942.

To all whom it may concern:

Be it known that I, JAY HERBERT SMITH, a citizen of the United States, residing at New Holland, in the county of Hall and 5 State of Georgia, have invented a new and useful Loom Attachment, of which the following is a specification.

This invention aims to provide novel means whereby, when the harness strap of a 10 loom breaks, and when the harness frame drops, the loom will be stopped.

It is within the province of the disclosure to improve generally and to enhance the utility of devices of that type to which the 15 invention appertains.

Although a preferred embodiment of the invention is shown in the drawings, it will be understood that that embodiment is inserted for the sake of illustration, merely, 20 and that a mechanic, working within the scope of what is claimed, may make such alterations as his skill and judgment may dictate, without departing from the spirit of the invention or avoiding the charge of 25 infringement.

In the drawings:—

Figure 1 shows in perspective, a device constructed in accordance with the invention, the same being mounted on a portion 30 of a loom, shown in dotted line; Figure 2 is an elevation showing a portion of a loom, the attachment claimed being mounted thereon, parts appearing in section; Figure 3 is a section on the line 3—3 of Figure 2; 35 Figure 4 is a section on the line 4—4 of Figure 1.

The numeral 1 marks the frame of a loom including a brace 2. The feeler 4 is carried by a shaft 5, supported for rocking movement, as indicated at 6, the feeler oscillating with respect to bars 3. The harness frame appears at 16, and the crank shaft at 28—all as understood readily by those familiar with the primary structural parts of 45 a loom.

In carrying out the invention, bearings 7 are mounted at 8, for adjustment, on the frame 1, and in the bearings, a shaft 9 is supported for rocking movement. The 50 shaft 9 is adjustable longitudinally in the bearings 7, but is held against longitudinal movement therein, through the instrumentality of collars 20, which, being secured adjustably at 21, to the shaft, coact with the

bearings 7 to prevent the shaft from moving endwise. 55

At one end, the shaft 9 is supplied with an upstanding first arm 10, having an inwardly prolonged extension 11, including a short depending finger 12. The finger 12 is so located that, when the shaft 9 is rocked, the finger will enter between the bars 3 and intrude into the path of the oscillatory feeler 4, the movement of the feeler being arrested, suitable intermediate devices (not shown) 60 operating to stop the loom, generally by releasing the shipper from its holding notch, this, however, being a detail in the construction of the loom, and having no especial bearing on the device which forms the subject matter of this application. 65

A means is provided whereby the finger 12 normally is held out of the path of the feeler 4, and with this end in view, the shaft 9 responds to the action of a retractile spring 75 23, to dispose the parts in the position depicted in Figure 2, one end of the spring being secured at 25 to the frame 1, and the other end of the spring being secured to the shaft 9, eccentrically of the shaft. It may 80 be expedient to attach the lower end of the spring 23 to a stop 22 on the shaft 9, as denoted by the numeral 24, the stop being adapted to engage the frame 1, as shown in Figure 4, and to limit the rotation of the 85 shaft 9, responsive to the action of the spring 23.

When the shaft 9 rocks, to interpose the finger 12 in the path of the feeler 4, some means should be provided for limiting the 90 rotation of the shaft 9 and, consequently, fixing the position of the finger 12 with respect to the feeler. Having this consideration in mind, the arm 10 on the shaft 9 is mounted somewhat loosely in an eye 14 95 forming part of a latch 15, mounted to reciprocate in an opening 17 fashioned in the brace 2, the latch having a shoulder 18 and being provided with a projection 19, spaced from the shoulder. It is clear that when the 100 arm 10 swings from the solid line position of Figure 2 to the dotted line position of that figure (to enable the finger 12 to stop the movement of the feeler 4), the projection 19, cooperating with the brace 2, or with any other accessible portion of the 105 loom frame, will limit the rotation of the shaft 9 and the swinging movement of the

arm 10. Having advanced from the solid line position of Figure 2, to the dotted line position therein delineated, the arm 10 cannot swing backwardly to the solid line position, because the shoulder 18 will engage with the brace 2. An operator, however, may move the latch 15 and disengage the shoulder 18 from the brace 2, whereupon the spring 23 will react, the stop 22 cooperating with the frame, and the parts being restored to the positions shown in solid line in Figure 2.

It is contemplated that the loom shall stop, when the harness strap breaks, and when the harness frame 16 drops. In order that this operation may take place, the shaft 9 is supplied with a second arm 26, disposed at an angle to the first arm 10, and comprising an extension 27, located approximately parallel to the shaft 9 and extended beneath one end of the harness frame 16. Obviously, when the harness frame 16 drops, the shaft 9 will be rotated, and the finger 12 will be interposed in the path of the feeler 4, as and for the purpose hereinbefore specified.

Having thus described the invention, what is claimed is:—

The combination with the harness and the feeler of a loom, of a movable member including an actuating part disposed in the path of the harness when the harness drops, and a stopping part movable into the path of the feeler when said member is actuated by the dropping of the harness; spring means for operating said member, thereby to retract the stopping part with respect to the feeler; means for limiting the movement of said member responsive to the spring means; and a combined means for limiting the movement of the stopping part toward the feeler and for holding the stopping part in operative relation to the feeler, said combined means being releasably under the control of an operator.

In testimony that I claim the foregoing as my own, I have hereto affixed my signature in the presence of two witnesses.

JAY HERBERT SMITH.
